UNITED STATES PATENT OFFICE.

JOHN M. HARTNETT, OF WAUKEGAN, ILLINOIS.

ARRANGEMENT OF MEANS FOR REGULATING THE FIRE OF COAL-BURNING LOCOMOTIVES.

Specification of Letters Patent No. 17,834, dated July 21, 1857.

To all whom it may concern:

Be it known that I, JOHN M. HARTNETT, of Waukegan, in the county of Lake and State of Illinois, have invented a new Arrangement of Means for Regulating the Fire of Coal-Burning Locomotives; and I do hereby declare that the following is a full, clear, and exact description of the same, reference being had to the annexed drawings, 10 making a part of this specification, in which—

Figure 1 is a longitudinal vertical and central section of my improvement. Fig. 2 is an inverted plan of ditto.

Similar letters of reference indicate corresponding parts in the two figures.

My invention consists in an arrangement of a fan blower placed underneath the boiler of the locomotive and connected with pipes which are provided with valves and so arranged that the fire may be supplied with a greater or less quantity of air as desired, and when necessary, a reverse draft brought down through the flues and the upper part of the fire chamber in order to lessen the temperature of the boiler. By this arrangement the fire may be regulated as desired with the greatest facility and placed under the complete control of the engineer.

To enable those skilled in the art to fully understand and construct my invention I will proceed to describe it.

A represents the boiler of a locomotive.

B is the smoke pipe.

C represents the flues which pass longitudinally through the boiler from the fire chamber D to the smoke-pipe B.

The above parts are of usual construction and therefore do not require a minute description.

Underneath the boiler A, a fan F is placed. This fan is fitted within a suitable cylindrical case or box G, which communicates at the center of each side with a curved pipe H, said pipe being connected with a pipe I, 40 which is fitted within the smoke pipe E, the upper end of pipe H passing through the front side of the smoke pipe. The way in which pipe I is made to communicate with the fan box is plainly shown in Fig. 2. A valve (a) is fitted in pipe I near its junction with pipe H.

From the periphery of the fan box G, two pipes J, K, project. The lower pipe K passes into the fire-chamber below the grate 55 L, and the end of pipe J communicates with

the open air. The pipes J, K, have valves (b), (b'), fitted or placed in them. These valves (b), (b'), are placed on a common rod or axis, and in reverse positions, so that when the upper valve (b) is open, the other 60 (b') will be closed and vice-versa.

M, M, represent two pipes, one end of which communicates with the fire-chamber above the grate L. The opposite ends of the pipes communicate with the sides of the fan box G. Each pipe M is provided with a valve (c). The valves of the several pipes all have rods (d) attached, which rods extend back at the sides of the fire-chamber and within reach of the engineer.

The fan F is driven by belts or chains (e) from one of the truck axles, the belts or chains being inclosed within proper cases to exclude dust and thereby prevent the wearing or "cutting out" of the same.

The operation is as follows: When an intense heat is required, the valves (c), (c) in the pipes M, M, are closed, and the valve (b) in the pipe J is also closed, and consequently the valve (b') in the pipe K will be open. 80 The fire will then be supplied with a blast which passes down the pipe I through the curved pipe H into the fan box G and thence through the pipe K into the fire-chamber D below the grate L and through the flues C into the smoke pipe B. See black arrows. The strength of this blast may be regulated by adjusting the valves (a) (b'). When the temperature of the boiler requires to be reduced, the valves (a) (b') are closed, and the 90 valve (b) in the pipe J opened, and the valves (c) in the pipes M, M opened. The blast will then pass down the smoke-pipe B through the flues C into the upper part of the fire-chamber D, and through the pipes M 95 into the fan box G, from whence it is discharged through the pipe J, as indicated by the red arrows. This reverse draft cools the pipes or flues C and reduces the temperature of the boiler. It will therefore be seen that 100

the coal fire is placed under the complete control of the engineer; for when an intense heat is required the blast indicated by the black arrows may be made sufficiently powerful to produce a rapid combustion, the 105 blast a short time after the fire is ignited being heated by passing down through the smoke pipe B. When the heat requires to be diminished, as in descending grades, the effect is obtained by the reverse draft which 110

as previously explained reduces the temperature of the boiler.

The great difficulty attending the burning of coal, and more especially anthracite coal 5 in locomotives has been the inability to control the fire, that is, varying its intensity as occasion may require.

The closing of the ash pan, and providing the flues C with dampers, the usual means 10 employed, will not answer for coal fires, for a slight draft is always formed or produced by leakage sufficient to keep the flues filled with the products of combustion, and an instantaneous action of effect cannot be produced. By my implement the temperature 15

of the boiler may be instantaneously reduced, and if a powerful fan is employed the temperature instantaneously raised.

Having thus described my invention what I claim as new and desire to secure by Letters Patent is—

The fan F placed within the box G connected with the pipes I, H, M, M, and J, K, provided with valves and arranged substantially as shown for the purpose set forth. 25

JOHN M. HARTNETT.
